UNITED STATES PATENT OFFICE

JOHN C. BLACK, OF DESTREHAN, LOUISIANA, ASSIGNOR TO AMERICAN LA FRANCE
AND FOAMITE CORPORATION, OF NEW YORK, N. Y., A CORPORATION OF NEW YORK

MIXING BOX FOR FOAM FIRE-EXTINGUISHING SYSTEMS

Application filed February 5, 1924. Serial No. 690,874.

The invention relates to fire protection systems for oil tanks or other containers for combustible liquids and consists in an improved discharge head, which constitutes a 5 mixing box for component foam making materials, adapted to be secured to the tank in position to discharge into it and embodying a closure member arranged to exclude tank vapors from the head and its associated pipe lines. The invention also consists in a discharge head of the foregoing 10 type so organized that the operation of the system will not be seriously impaired as the result of an explosion within the tank on 15 which the head is mounted.

The invention is exemplified in preferred form in the accompanying drawings, in which:

Fig. 1 is a view partly in section of my 20 device attached to a cone roof tank.

Fig. 1^a shows a modification wherein the device is shown attached to a water sealed roof tank.

Fig. 2 is a view at right angles to that 25 shown in Fig. 1; and,

Fig. 3 is a cross section of the flange and diaphragm used in my device.

1 is a tank having the ordinary roof 2, in which a hole 3 is made with bolt holes 30 around it. Connected to the roof in line with the hole 3 is a spout 4 having a flange 5 thereon.

Attached to the upper edge of the tank 1 is a bracket 6. This bracket is securely and 35 strongly attached to the tank by means of bolts or rivets 7 and extends up over the discharge head or mixing box 8 and may be bolted thereto by bolts 9. The outlet from the head is directed over the top of the tank 40 wall and inwardly of the tank and is flanged, as at 10. Between the flanges 5 and 10 are secured by bolts 20, a diaphragm 11 and on either side of this diaphragm are ring gaskets 12. The bolts 20 are made sufficiently small to yield or give away by an 45 explosion in the tank if the roof was blown off or ruptured, the bracket 6 being made sufficiently strong to hold the main portion of the box in position to mix and deliver 50 the foam into the tank 1. The flanges 5 and

10 clamp the gaskets between them and the gaskets in turn clamp the diaphragm 11 forming an oil and vapor tight connection, so that should any vapors from the oil pass up the spout 4 they will be prevented from 55 passing over into the main portion of the head and pipe lines 17 and 18.

The diaphragm 11 is ordinarily made of paper or some similar material and coated and impregnated with a varnish or impervious coating to resist the action of the oil and water vapors. The head 8 has a bottom 15 and it is ordinarily connected to the side of the tank 1 by an additional bracket 16.

In case of fire in the tank 1, chemicals such as bicarbonate of soda mixed with a foaming material are pumped through a pipe 17 and another chemical such as sulphate of aluminum is pumped through the 70 other pipe 18. These two chemicals meeting in the box 8 will immediately foam up through the box and will exert sufficient pressure to burst the diaphragm 11 and the foam will flow through the spout into the 75 tank to extinguish the fire.

In case the top of the tank shown in Fig. 1 is ruptured or blown away by explosion, thus displacing this part of the discharge 80 portion of the box attached to the tank, the bracket 6 is sufficiently strong to maintain the foam box in position to conduct the foam into the tank, especially when the parts are additionally held by a bracket like 16.

Fig. 1^a shows a modification in which the spout 4 of the box is extended down through the water seal at the top of the tank and is attached by means of a flange to the metal 85 top 2' of the tank.

These boxes from actual test have proven very efficient, the diaphragm 11 when properly treated will last for an indefinite period, the parts of the apparatus are easily and cheaply constructed and assembled and are 90 exceedingly efficient.

I claim as my invention:

1. In a fire protection system the combination of a tank, a foam delivery head 100 adapted to be secured thereto and arranged

to discharge into the tank, a rupturable diaphragm associated with the head outside of the tank and precluding flow of tank vapors into the head, said diaphragm having a tensile strength less than the pressure of the foam.

2. In an oil tank fire protection system, the combination with a closed oil tank, of a conduit for conducting foam under pressure to the upper interior of said tank, a joint in said conduit outside the tank and a rupturable diaphragm clamped in said joint precluding flow of vapor from the oil in said tank through said conduit and having a tensile strength less than the pressure of the foam to be delivered thereto.

3. A foam fire extinguishing system comprising an oil tank, a foam delivery box disposed on the side of the tank and having an outlet outside of the tank positioned to discharge foam into its interior, means to hold said box securely in place, a conduit connected to the aforesaid outlet of the box and extending inwardly of said tank wall and means to fasten the adjacent ends of the conduit and box together, said means having a tensile strength less than the means holding the box in place, whereby blowing away of said conduit will leave said box in place to deliver foam into the tank.

4. A foam fire extinguishing system comprising a tank having a top with a hole therein, a foam delivery box disposed outside of said tank, said box having an outlet portion positioned to discharge foam over the tank wall and into said tank, means to securely hold said box in place, a conduit connected to said outlet of the box and extended inwardly of said tank wall to discharge through said hole in the tank top, a rupturable diaphragm associated with said conduit and precluding the flow of vapors from said tank to said box, said diaphragm having a tensile strength less than the pressure of the foam, and means to fasten the adjacent ends of the conduit and box together, said last mentioned means having a tensile strength less than the means holding the box in place whereby, if the conduit is blown off the box remains in place to deliver foam into the tank.

In testimony whereof I hereunto affix my signature.

JOHN C. BLACK.
